TRUSS STRUCTURE

Hamilton L. Loudenback, Sidney, Ohio, assignor
of one-third to Clarence F. Loudenback, Sid-
ney, Ohio

Application November 3, 1931, Serial No. 572,825

4 Claims. (Cl. 108—23)

This invention relates to a truss structure, and it is primarily an object of the invention to provide a built-up wooden structure wherein the constructive parts are arranged edgeways, crossways and diagonal to their different strains and wherein all of such parts are arranged on edge with respect to the load or stress imposed thereon.

Furthermore, it is an object of the invention to provide a structure of this kind wherein all of the constructive parts comprised therein are at rest or, in other words, free of bending, stretching or compressive strains until after it has been placed in desired working position and live and dead loads are superimposed thereon.

An additional object of the invention is to provide a wooden truss structure wherein the various constructive parts are used in their natural grown state and wherein the various parts are assembled or built in the structure end to end, or end grain to end grain, thereby preventing any distortion as a result of shrinkage in materials.

A still further object of the invention is to provide a structure of this kind comprising in its building the use of sheathing, the sheathing members being so applied and held in place that said sheathing members will act in their natural shrinkage to tighten instead of loosening due to the fact that certain of the sheathing members will shrink in opposite directions from that of other of the sheathing members.

The invention also contemplates a wooden truss structure comprising upper and lower convex and concave segments or chord members with interposed struts, said members comprising a continuous arched structure adapted to be supported from one supporting pier or foundation to the other with any desired curvature required by span and height.

A still further object of the invention is to provide a truss structure of this kind wherein the soffit or under surface of the truss is disposed on radii struck from two points slightly above and to the right and left of the point or center from which is struck the curvature of the outer surface of the top segments or chord members at the central portion thereof, thus increasing the strength of each leg of the truss against cross bending and where such strength is most needed to prevent spreading.

Still another object of the invention is to provide a truss structure wherein the parts are so constructed and assembled that all live and dead load strains imposed thereon, either by compression, tensile, or bending, are counteracted by the various parts or members built in the truss

structure due to the fact that such parts or members are disposed at different angles relative to each other which results in a truss structure having a self contained, rigid and firm, unyielding structure and which construction also brings the truss under the slow burning class of wood truss construction.

The invention consists in the details of construction and in the combination and arrangement of the several parts of my improved truss structure whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view partly in section and partly in elevation illustrating a truss structure constructed in accordance with an embodiment of my invention;

Figure 2 is a fragmentary diagrammatic view indicating the radii for the different curvatures of the structure;

Figure 3 is an enlarged fragmentary sectional view taken substantially on the line 3—3 of Figure 1;

Figure 4 is an enlarged fragmentary sectional view taken substantially on the line 4—4 of Figure 1;

Figure 5 is a fragmentary sectional view taken substantially on the line 5—5 of Figure 3;

Figure 6 is a sectional view taken substantially on the line 6—6 of Figure 3;

Figure 7 is a sectional view taken substantially on the line 7—7 of Figure 3.

In Figures 1 and 2, the truss structure as illustrated comprises slightly more than one-half of the length of such structure. It is to be understood, however, that the opposite end portions of the structure are similar and, therefore, it is believed that the illustration made by Figures 1 and 2 is sufficient for the purposes of disclosure.

My truss structure as herein disclosed comprises two chords A and B and each of these chords comprises the segments 1 and 2 respectively. The segments of each of the chords constitute timbers of desired dimensions and cut from wood in its natural state in desired form and with its grain running lengthwise thereof so that when adjacent segments 1 or 2 are arranged

in assembled relation they are in butting contact with the grain of the segments end to end. These segments do not have to be of any material length but, on the contrary, I find it of particular advantage to produce such segments from short lengths thus materially reducing the cost of production.

The joints 3 of one of the chords are staggered with respect to the joints of the second chord 10 thus assuring the segments of one of the chords being in effective lapping relation with the segments of the other chord so that said chords A and B from end to end will be substantially the same as if constructed from continuous pieces 15 of material. The segments 1 and 2 of the chords A and B respectively have interposed therebetween the diagonally disposed and crossed bracing or reinforcing struts or buck-staying members 4, the extremities of which being nailed or 20 otherwise effectively secured or anchored to the opposed surfaces of the chords A and B.

It is to be particularly noted that each strut or member in this construction of the truss herein disclosed extends from an end portion of a segment 25 of one chord to approximately the center of an adjacent segment of the second chord thus assuring effective binding or holding together of the chords A and B. It is also to be noted that each of the struts or buck-staying members 4 is 30 of a thickness equal to the thickness of the chord members A and B and that they are arranged end to end and in butting contact. Each strut or member 4 is also in the same plane as the chords A and B.

35 As is particularly illustrated in diagrammatic Figure 2, the central part of the outer surface of the upper or top chord A is disposed on a radius struck from a desired point *a* midway of the ends of the truss structure. The soffit or 40 under surface of the lower or bottom chord B at its central portion is disposed on radii struck from the points *b* and *c* at desired distances above and to the right and left of the point *a*, the points *b* and *c*, however, being equidistantly spaced with respect to the vertical radius from 45 the point *a*. The portion of the soffit or under surface of the chord B to one side of the vertical radius of the central portion of the truss is struck from the point, such as *b*, to the opposite side of the vertical radius while the portion of the soffit or under surface at the opposite side of the vertical radius from the point *a* is struck from the point at the opposite side of the vertical radius. These curvatures of the top 50 surface of the chord A and the soffit or under surface of the chord B at the central portion thereof are of particular and especial importance and advantage as they result in the truss structure having a taper from below or within from 55 the ends or feet of the structure to the center thus increasing the strength of each leg or one-half of the truss structure against cross bending and which strength is most needed to prevent spreading of the structure.

60 Each end portion of the truss may be disposed on such curvatures as deemed most effective and, as illustrated in diagrammatic Figure 2, the outer surface of the top chord A is struck from a point *d* positioned a desired distance inwardly of the adjacent end of the truss and above the horizontal while the soffit or under surface of the inner or bottom chord at the adjacent end portion is on a radius struck from the point *e* spaced a desired distance above but in vertical 65 alignment with the point *d*.

The chords A and B, in addition to the struts 4, are tied or held in desired assembled relation by the sheathing nailed or otherwise attached to the opposite side faces of the segments 1 and 2 of the chords A and B respectively and also nailed or otherwise anchored or secured to the struts 4. The members 5 of these sheathings are 70 diagonally disposed with respect to the longitudinal axis of the truss with the members 5 of the sheathing at one side being reversely disposed with respect to the members 5 of the sheathing at the opposite side. These members 5 are preferably disposed on an angle of forty-five degrees with respect to either the horizontal or vertical. This reverse arrangement of the 15 members 5 of the sheathings at opposite sides of the chords A and B is of particular advantage in view of the fact that any shrinkage of these members 5 which may occur will result in tightening the structure instead of loosening as the 20 shrinkage of the members of one of the sheathings will be in a direction opposite to the shrinkage of the members of the other sheathing at the opposite side. Adjacent members of each of the sheathings are preferably interlocked by the 25 well known tongue and groove structure, as indicated at 6.

The grain of the members 5 is that of natural mill sawed lumber with the grain markings running the length of the member. There is no shrinkage in lumber except in its width and thickness and with the members 5 of one of the sheathings deployed in a direction opposite to that of the members of the second sheathing, the shrinkage of the different plies of sheathings 30 will tend to tighten the structure.

The members 5 of the sheathings extend beyond the outer curved edge or face of the chord A and are also secured to the opposite faces of the segments 1 comprised in the ridge member R. This ridge member R extends as desired along the upper portion of the truss structure from the center thereof and also preferably consists of segments or pieces arranged end to end in butting relation and with the grain of the 40 members also end to end. As illustrated in Figure 1, each end portion of the ridge member R is extended outward on desired curvature or otherwise as preferred and extends to a wall line post 8 to which it is nailed or otherwise suitably anchored. The sheathing associated with each of the chords A and B is also extended to afford connection with this wall line post 8 and to the extended end portion 9 of the ridge member thus providing a rigid triangle end whereby the strength and value of the truss structure in its 45 entirety is materially increased.

The members 5 of each of the sheathings have secured thereto the upper and lower chord or compression members A' and B' arranged in overlying relation with respect to the chord members A and B and coincident in design or configuration therewith. These compression members A' and B' are also formed of segments 1'. These segments each comprise a timber of desired dimensions and arranged in the same manner as hereinbefore set forth with respect to the segments or timbers 1. It is to be particularly stated that the joints 3' between adjacent segments or timbers 1' alternate with the joints 3 between the segments or timbers 1 of the chords A and B. These compression members A' and B' also have interposed therebetween and secured to the members 5 of the sheathings the diagonally disposed crossed struts or buck-stay- 50 55 60 65 70 75 80 85 90 95 100

ing members 4' for the same purpose as hereinbefore set forth with respect to the struts 4. These struts or members 4' are also each of a thickness equal to the thickness of the chords 5 A' and B' and occupy the same plane and these struts or members 4' are also arranged end to end and in butting contact.

Disposed over these compression members A' and B' and intermediate struts 4' are the additional sheathings comprising the diagonal members 5'. The members 5' of each of these additional sheathings are reversely related one with respect to the other and also reversely related with respect to the members 5 of the 15 adjacent sheathings. This arrangement of these additional sheathings, or more particularly the members 5', with respect to the members 5 of the first named sheathings results in a structure wherein all of the parts are effectively tied 20 together to assure a rigid and non-yielding structure.

The structure as hereinbefore described results in the production of what may be properly termed a "multi-ply arched truss", said truss 25 being of a character whereby the assembly of the structural members comprised therein is such to prevent distortion of the truss and whereby the fire hazard is reduced to a minimum. While it may be true that the truss will burn its structure 30 is such whereby the truss will not quickly lose strength when heated. A considerable length of time must elapse before the truss is burned through sufficient to cause failure. The particular placement of the sheathing members 5 and 5' 35 is such whereby said sheathing members function in offering resistance to the compressive, tensile, and cross bending strains that occur within the truss that may be created by the superimposed load to be supported on the truss.

40 It is to be stated at this time that the truss structure can be built on any desired curved lines from a true circle, elliptical circle, or parabola, or with various other curves and radii of arch forms changing in length in accordance with the 45 dimensions of the building and load requirements of the structure. It is to be understood, however, that in each of such instances the structure will retain the off center curves for the under surface or soffit of the structure to provide a taper 50 on the under side of the arch to increase the resisting strength to cross bending.

It is also to be stated that as many compression members A' and B' arranged in side by side relation with interposed sheathings may be employed as the requirements of practice may 55 dictate.

At predetermined spaced points along its upper portion the ridge member R and the adjacent portions of the members 5 of the sheathings are provided with upwardly opening notches or recesses 10 with which interlock portions of the rafters 11, said rafters having their upper margins flush with the top faces or surfaces of the ridge member R and adjacent members 60 5 so that the roofing sheathing boards or members 14 may be conveniently applied. In order to increase the esthetic value of the arch structure I find it desirable under certain conditions to interpose between each of the outer sheathings 5 and the adjacent portions of the rafters 11 the bracket strips 15. While these brackets 65 15 to a considerable extent increase the strength of the roof structure supported by the truss structure, yet these brackets 15 are of especial 70 advantage in the formation of what may be

75 termed coves to facilitate the interior finish of the wall structure as by plaster or other materials.

Relative to the truss structure proper, it has also been found of advantage to tie or connect the segments or timbers of each of the chords A and B and the associated compression members A' and B' by the bolts 16, said bolts extending through said segments or timbers and also through certain members 5 and 5' of the sheathings. Each of the bolts 16 has associated therewith a conventional nut 17 to facilitate its maintenance in applied position.

It is again to be emphasized that none of the parts comprised in the truss structure are bent 15 or flexed and that each of the various parts or members is cut out from the natural wood in desired shape, thus assuring a truss structure when completely assembled to be entirely free of stress within itself or, in other words, to provide 20 a truss structure which is only subjected to the stress imposed thereon by the load it supports.

While the sections 1 and 2 of the chords A and B and the corresponding sections 1' and 2' of the compression members A', and B' have been referred to as segments and thus implying longitudinal curvature, it is to be understood that for all practical purposes this definition is intended to embrace the idea of multiple straight line arch, the sections in this multiple straight line arch 30 being arranged and assembled in the truss structure in the same manner as hereinbefore described with respect to the segments.

From the foregoing description it is through 35 to be obvious that a truss structure constructed in accordance with my invention is particularly well adapted for use by reason of the convenience and facility with which it may be assembled and operated, and it will also be obvious that my invention is susceptible of some change and 40 modification without departing from the principles and spirit thereof and for this reason I do not wish to be understood as limiting myself to the precise arrangement and formation of the several parts herein shown in carrying out my 45 invention in practice except as hereinafter claimed.

I claim:—

1. A wooden multi-ply arched truss structure comprising spaced upper and lower chord members, each of said chord members comprising segments arranged end to end and in butting contact, sheathing members connected to the opposite faces of the chord members and bridging the space therebetween, compression members secured against the outer faces of the sheathing members at opposite sides of the upper and lower chord members, said compression members also comprising segments arranged end to end and in butting contact, sheathing members secured to the outer faces of the compression members and bridging the space therebetween, the sheathing members being diagonally disposed with the members of the sheathing at one side of the chords being inclined in a direction opposite to the inclination of the sheathing members at the opposite side of the chords and the sheathing members secured to the outer faces of the compression members being inclined in a direction opposite to the inclination of the sheathing members connecting the chord members, struts interposed between and coplanar with the segments of the upper and lower chords, and additional struts interposed between and coplanar with the compression members of the upper and lower chords. 75

2. A wooden multi-ply arched truss structure comprising spaced upper and lower chord members, each of said chord members comprising segments arranged end to end and in butting contact, sheathing members connected to the opposite faces of the chord members and bridging the space therebetween, compression members secured against the outer faces of the sheathing members at opposite sides of the upper and lower chord members, said compression members also comprising segments arranged end to end and in butting contact, sheathing members secured to the outer faces of the compression members and bridging the space therebetween, the sheathing members being diagonally disposed with the members of the sheathing at one side of the chords being inclined in a direction opposite to the inclination of the sheathing members at the opposite side of the chords and the sheathing members secured to the outer faces of the compression members being inclined in a direction opposite to the inclination of the adjacent sheathing members connecting the chord members, struts interposed between and coplanar with the segments of the upper and lower chords, and additional struts interposed between and coplanar with the compression members of the upper and lower chords, the struts between the chord members and the struts between the compression members being in crossed relation.
3. A wooden multi-ply arched truss structure comprising spaced upper and lower chord members, each of said chord members comprising segments arranged end to end and in butting contact, sheathing members connected to the opposite faces of the chord members and bridging the space therebetween, compression members secured against the outer faces of the sheathing members at opposite sides of the upper and lower chord members, said compression members also comprising segments arranged end to end and in butting contact, sheathing members secured to the outer faces of the compression members and bridging the space therebetween, the sheathing members being diagonally disposed with the members of the sheathing at one side of the chords being inclined in a direction opposite to the inclination of the sheathing members at the opposite side of the chords and the sheathing members secured to the outer faces of the compression members being inclined in a direction opposite to the inclination of the adjacent sheathing members connecting the chord members, struts interposed between and coplanar with the segments of the upper and lower chords, and additional struts interposed between and coplanar with the compression members of the upper and lower chords, the struts between the chord members and the struts between the compression members being in crossed relation.

the segments of the upper and lower chords, and additional struts interposed between and coplanar with the compression members of the upper and lower chords, the struts between the chord members and the struts between the compression members being in crossed relation, the struts between the chord members and also the struts between the compression members being arranged end to end, the struts between the chord members extending from the extremities of the segments of one chord member to the central portions of the segments of the second chord member, the struts between the compression members being similarly extended.

4. A wooden multi-ply arched truss structure comprising spaced upper and lower chord members, each of said chord members comprising segments arranged end to end and in butting contact, sheathing members connected to the opposite faces of the chord members and bridging the space therebetween, compression members secured against the outer faces of the sheathing members at opposite sides of the upper and lower chord members, said compression members also comprising segments arranged end to end and in butting contact, sheathing members secured to the outer faces of the compression members and bridging the space therebetween, the sheathing members being diagonally disposed with the members of the sheathing at one side of the chords being inclined in a direction opposite to the inclination of the sheathing members at the opposite side of the chords and the sheathing members secured to the outer faces of the compression members being inclined in a direction opposite to the inclination of the adjacent sheathing members connecting the chord members, struts interposed between and coplanar with the segments of the upper and lower chords, and additional struts interposed between and coplanar with the compression members of the upper and lower chords, a ridge member extending along the upper chord member, the end portion of the ridge member extending outwardly beyond the upper chord member, and wall line posts for supporting the outer parts of the extended portions of the ridge member, the sheathing secured to the opposite faces of the chord members being extended for securement to the opposite faces of the ridge member and the extended portions thereof and also the opposite faces of the wall line posts.

H. L. LOUDENBACK.
